TOILET TISSUE DISPENSER

Hugh E. McCants, Houston, Tex., assignor to
Reserv-A-Roll Company

Application October 18, 1954; Serial No. 463,020

3 Claims. (Cl. 242—55.3)

This invention relates to article dispensing machines and more particularly to machines for dispensing toilet tissue in rolls.

This application is a continuation-in-part of my co-pending application, Serial No. 353,533, filed May 7, 1953.

The principal object of the present invention is to discourage pilfering of toilet tissue from public rest rooms by transients and others, causing financial loss and inconvenience for those responsible for the maintenance of the rest rooms.

Another object of the invention is to provide an inexpensive but efficient toilet tissue dispenser which is designed to be either recessed in a wall or suspended thereon but in any case, is adapted to contain in superimposed relationship, a plurality of rolls of toilet tissue, the lowest roll being the only one accessible to the user but which is locked against other than rotative movement for the dispensing of tissue.

Another object of the invention is to provide a toilet paper dispenser cabinet which is hinged at its bottom for outward tilting displacement for filling and is lockable in closed position, there being in the cabinet but one opening to expose a single roll in dispensing position, except for small slots or windows in the sides of the cabinet to determine the need for replenishment.

Still another object of the invention is to provide means for collecting and storing spindles or rollers from which the toilet paper has been dispensed. Such depleted rollers are pressed downwardly past the restraining means at the dispensing position and drop into the bottom of the cabinet from which they are collected for reuse when the cabinet is replenished, thus obviating the annoyance and expense of loss or misplacement of the rollers.

Other objects will appear as the description proceeds when considered with the annexed drawing, wherein:

Figure 1 is a side view of the invention in vertical section.

Figure 2 is a front elevational view with parts broken away.

Figure 3 is a top plan view with a portion of the cabinet broken away; and

Figure 4 is a fragmentary perspective view showing the means for restraining a roll of paper in dispensing position.

Continuing with a more detailed view of the drawing, reference numeral 10 denotes generally the cabinet containing the elements of the dispenser and which consists of an elongate shell 11 having an open rear and which is hinged at 12 to a wall mounting plate 13. The mounting plate 13 is secured, as by screws, to a wall and is provided with parallel side flanges 14 which are received by the cabinet shell 11 when the latter is in closed position. The cabinet has elongate beads or ribs 15 formed in each side wall and spaced inwardly from the rear edges thereof to reinforce the cabinet. A suitable key lock 16 se-

2
cures the cabinet in closed position to prevent unauthorized removal of paper rolls therefrom.

The paper rolls are each indicated by reference numeral 17 and these are of conventional manufacture, each containing the usual cardboard core. In order to adapt these rolls to the dispenser herein disclosed, it is only necessary to insert a spindle 18 of wood or other suitable material into the core of the roll of paper. These spindles are also conventional and each has a pintle 19 formed on each end of a diameter less than that of the spindle itself.

To the interior surface of each side wall of the cabinet 10 is secured a track 20. The tracks are identical except for reverse construction which disposes them in confronting relationship to receive opposite ends of the spindles 18. The tracks are each die formed in one piece to define a channel 21 and side flanges 22 and 23. The tracks are secured to the side walls of the cabinet 10 as by spot welding or by rivets, as indicated at 24, in the webs of the channels 21.

It will be observed that the upper vertical portions of the tracks 20 are or can be of sufficient length as to accommodate as many rolls 17 of paper as may be desired, although the drawing shows but two. At a point below the midsection of the tracks, the channels 21 turn downward in a forwardly direction and are again directed vertically downward. This arrangement of the tracks causes the lowest roll 17 of the column of rolls to be thrust partially out of the cabinet 10 through a dispensing opening 25 in the front of the cabinet. This opening has rolled edges 26.

To fill the cabinet 10 with rolls 17, it is unlocked and lowered on its hinge 12 to the limit of a pair of chains 27, each having an end secured to a hook 28 on the mounting plate 13 and its opposite end attached in a hole 29 on the flange 23 of a track 20. The rolls are placed in the machine so that the pintles 19 of their spindles 18 will be received in the confronting channels 21 of the tracks 20. The first roll deposited into the dispenser is intercepted by a pair of arms 30 whose upper ends 31 lie in the paths of the pintles 19 as they move downwardly in the channels 21.

The arms 30 are each pivoted at its lower end to the lower end of a track flange 23 by means of a rivet 32 having a countersunk head. The arm extends upwardly and rearwardly and is turned to extend upwardly and forwardly so that its upper end 31 may extend into a channel 21 through a vertical slot 33 in one side thereof. One corner of the upper end of each arm 30 is removed to form a flat portion 34 which bears against the wall of the channel 21 opposite the slot 33.

A substantially U-shaped restraining and releasing lever 35 is provided to actuate the arms 30, its function being two-fold. Primarily, the lever 35 restrains a roll 17 of toilet tissue in the dispensing position shown and also functions to displace the arms 30 to release the next succeeding roll 17 when the first roll is depleted.

The lever 35 has parallel legs 36, each having an end 37 which enters a channel 21 through a slot 38 in one wall thereof. Each leg 36 of the lever 35 is spot welded at 39 to a respective arm 30 so that the arms will move when the lever moves. Normally, the lever 35 is held with its legs extended into the channels 21 through the medium of the arms 30 by means of leaf springs 40, each being affixed at 41 at its upper end to a rear wall of a channel 21, the springs being disposed to bear against the rear edges of the arms 30 adjacent their upper ends to resist outward displacement of the arms, thereby holding the lever 35 in extended or operative position.

As stated previously, the first roll of tissue entering the cabinet will be intercepted in the vertical portion of

3

the tracks by the upper ends of the arms 30. These arms will be moved manually outward to allow the first roll to pass downwardly to the dispensing position but in the meantime, the arms 30 are permitted to resume the position shown in Figure 1 so that the ends 37 of the legs 36 of the lever 35 will intercept the first roll and hold the same in dispensing position. The magazine composed of the tracks 20 is then filled to capacity with tissue rolls whereupon it is closed and locked.

In operation, toilet tissue is removed from the bottom roll 17 until depleted, leaving only the spindle 18 supported by the ends 37 of the legs of the lever 35. By slight pressure imposed downwardly on the empty spindle or roller 18, the lever 35 is thrust inwardly against the resistance of the leaf springs 40. The empty spindle 18 will thus be released and will fall into the space 42 provided therefor in the bottom of the cabinet 10 from whence the rollers are removed for reuse.

Simultaneously with the actuation of the lever 35 with the described result, the arms 30 are moved on their pivots 32, causing their upper ends 31 to recede from their respective slots 33 in the walls of the channels 21, thus removing the supports from under the spindles 18 of the next succeeding roll of tissue 17, permitting it to drop downwardly in the tracks. Before the spindles of the roll 17 reach the dispensing position, the springs 40 will have returned the arms 30 to their normal supporting position to intercept the next higher roll 17 while at the same time returning the lever 35 to its normal supporting position to intercept the roll just released by the arms 30.

It will be observed in Figure 1 that the spindle 18 carrying the tissue roll in dispensing position cannot be removed from the machine even when all of the paper has been unwound therefrom. Therefore, the rollers or spindles cannot become lost or misplaced and are always found in their proper place in the bottom of the cabinet when it becomes necessary to restock the cabinet.

To determine when the cabinet requires restocking, windows 43 are provided in the side walls through which can be seen the tracks 20.

It is evident from the foregoing that losses sustained by rest room owners because of pilfering of toilet tissues is reduced to a minimum and however small these losses may be, the annoyance occasioned by such pilfering is considerable but is also obviated by the invention.

Manifestly, the construction as shown and described is capable of some modification and such modification as may be construed to fall within the scope and meaning of the appended claims is also considered to be within the spirit and intent of the invention.

What is claimed is:

1. A machine for dispensing toilet tissue from rolls, comprising a cabinet closed except for a dispensing opening in its lower front, opposed confronting channels on the side walls of said cabinet adapted to receive the ends of spindles carrying said rolls in superimposed relationship in said cabinet, said channels each having an upper vertical portion midway of said side walls, a lower vertical portion disposed forwardly adjacent said dispensing opening and an inclined portion interconnecting said vertical portions, an arm pivoted at its lower end adjacent the lower end of each of said channels and having its upper end engaging in the upper vertical portion of said channel to support all but one of said tissue rolls, means connecting said arms for simultaneous movement, means carried by said arms adapted to engage in the lower vertical portions of said channels to define supports for the spindle of said one of said rolls in dispensing position of the latter in said dispensing opening, means biasing said arms into channel engaging position said biasing means being

overcome by finger pressure downwardly on an empty spindle in dispensing position to retract the support of said arms to release said empty spindle into said cabinet while releasing the next higher roll to replace said empty spindle in dispensing position, said arms resuming their positions in support of said released roll and the remainder of rolls, respectively, under the action of said biasing means.

2. A machine for storing and dispensing toilet tissue from rolls, each having a spindle, a cabinet closed except for a dispensing opening in its lower front, confronting channels on the side walls of said cabinet receiving the ends of the spindles of said rolls in superimposed relationship, said channels extending downwardly, forwardly toward said dispensing opening and downwardly therebelow, a first means spring biased into said channels above said dispensing opening for intercepting the spindles of all but one of said rolls, a second means stationary with said first means normally biased into said channels opposite said dispensing opening for intercepting the spindle of said one of said rolls for accessibility of the latter through said dispensing opening, said first and second means comprising, respectively, a pair of curved arms pivoted at their lower ends to the sides of said cabinet and whose upper ends engage in said channels above said dispensing opening and a member in fixed relationship with said arms and extending into said channels at said dispensing opening, said first and second means being retractable by finger pressure on an emptied spindle to replace the latter by the next higher roll, said first and second means resuming their positions in said channels under the action of said biasing means to support the replaced rolls.

3. A machine for storing and dispensing tissue from rolls having spindles, comprising a cabinet closed except for a dispensing opening in its lower front, said cabinet having a wall plate to which it is hinged along its lower inner edge for tilting displacement during replenishment thereof with tissue rolls and means for locking said cabinet to said wall plate, a channel on each side wall of said cabinet, said channels being in confronting relationship to receive the ends of spindles carrying rolls in superimposed relationship in said cabinet, a first means slidably in said channels above said dispensing opening to support the spindles of all but one of said rolls, a second means rigid with said first means for supporting the spindle of said one of said rolls adjacent said dispensing opening, said first and second means comprising, respectively, a pair of curved arms pivoted at their lower ends to the sides of said cabinet and whose upper ends engage in said channels above said dispensing opening and a member in fixed relationship with said arms and extending into said channels at said dispensing opening, spring means biasing said first and second means into said channels, said first and second means being simultaneously retractable from said channels by downward pressure imposed on an emptied spindle supported by said second means to release said spindle into said cabinet and to release the next highest roll into dispensing position to replace said empty spindle, said first and second means resuming their positions in said channels to support the superimposed rolls and the replacing roll, respectively, under the action of said biasing means.
